UNITED STATES PATENT OFFICE.

JAY E. CROSS, OF SOUTH LANCASTER, MASSACHUSETTS.

DESIGN FOR A POWDER-CONTAINER.

45,586.

Specification for Design.

Patented Apr. 14, 1914.

Application filed December 16, 1913. Serial No. 807,130. Term of patent 3½ years.

To all whom it may concern:

Be it known that I, JAY E. CROSS, a citizen of the United States, residing at South Lancaster, in the county of Worcester and State of Massachusetts, have invented a new and useful original and ornamental Design for a Powder-Container, of which the following is a specification, reference being had to the accompanying drawing, forming part thereof.

The drawing is a front view of a powder container showing my new design.

I claim:

The ornamental design for a powder container as shown.

JAY E. CROSS.

Witnesses:

ALBERT E. FAY,
C. FORREST WESSON.
